UNITED STATES PATENT OFFICE.

MORRIS H. BROWN, OF PENN YAN, NEW YORK, ASSIGNOR TO JACOB DAVIS, OF PENN YAN, NEW YORK.

CHECK-CONTROLLED DISPENSING MECHANISM.

1,050,608.

Specification of Letters Patent.

Patented Jan. 14, 1913.

Original application filed March 25, 1912, Serial No. 686,013. Divided and this application filed May 9, 1912. Serial No. 696,151.

To all whom it may concern:

Be it known that I, MORRIS H. BROWN, a citizen of the United States, residing at Penn Yan, in the county of Yates and

5 State of New York, have invented certain new and useful Improvements in Check-Controlled Dispensing Mechanism, of which the following is a specification.

This invention relates to that class of dispensing apparatus which is controlled by a coin or predetermined denomination.

The present case is a division of the application Filed March 25, 1912, Serial No. 686,013, and it relates to a device for returning a coin to the patron if the supply of material is exhausted.

In the accompanying drawing forming a part of this specification—Figure 1 is a vertical section of the apparatus showing the 20 application of the invention. Fig. 2 is a section on the line 2—2 of Fig. 1.

Referring specifically to the drawing, 10 denotes a cabinet which incloses the delivery and coin mechanism. The cabinet 25 has a compartment 11 which is designed to hold loose goods, such as candy, nuts, etc., the same being delivered in measured quantities. The delivery mechanism forms no part of the present invention and need 30 therefore not be illustrated nor described in detail.

At 12 is shown a coin-chute which carries the coin to the delivery mechanism. Associated with the coin-chute are fraud-preventing devices which are the subject matter of companion applications.

In order to return a coin to the patron, if the supply of material to be delivered is exhausted, the following mechanism is provided: Near the bottom of the compartment 11 is a bracket 13 which supports a rod 14 which is free to rock and carries a shelf 15.

The rod extends from the compartment and has a bend 16 which extends through registering slots 17 in the walls of the coin-chute 12.

The weight of the loose goods on the shelf 15 swings the latter down, thereby rocking the rod 14 in a direction to swing the bend 16 upward in the coin-chute a sufficient distance to allow the coin to pass. After all the goods have been delivered, the shelf rises, and the bend 16 lowers in the coin-chute so as to block the passage of the coin to the delivery mechanism. The last described movement of the parts is effected by means of a weight 18 carried by the extremity of the bend 16. The coin is then returned to the outside of the machine by the mechanism described and claimed in the 60 case, Serial No. 686,013.

I claim:

1. In a coin-controlled vending machine, a coin chute, a receptacle for the goods to be delivered, a swinging shelf at the bottom of the receptacle, and a rod connected to the shelf and having a barrier extending across the coin chute.

2. In a coin-controlled vending machine, a coin chute, a receptacle for the goods to be delivered, a swinging shelf at the bottom of the receptacle, said shelf being lowered by the weight of the goods thereon, means for raising the shelf when the weight is removed therefrom, and a barrier carried by the shelf and extending across the coin chute.

In testimony whereof I affix my signature in presence of two witnesses.

MORRIS H. BROWN.
